UNITED STATES PATENT OFFICE

2,600,771

INSTRUMENT HOLDER

Victor E. Höfmann, Toledo, Ohio

Application November 13, 1947, Serial No. 785,599

8 Claims. (Cl. 224—4)

1

This invention relates to holding means or supports for chronometers, stop watches, pocket compasses and the like, and one object of the invention is to provide a simple, detachable means or holder by which a person may carry a stop watch or similarly shaped instrument in the hand and be assured that it will remain securely therein even though at the same time the fingers may be engaged in manipulating parts of the watch or other instrument without requiring the assistance of one's other hand.

Another object is to provide a construction for a holder as mentioned whereby the holder may be rendered adaptable to fit the average size of watch case or other instrument although the watch or instrument cases may vary slightly in thickness or diameter, or the bail may be of greater or lesser proportions.

Further object of the invention resides in the provision of a holder for chronometers or similar instruments which may be readily applied to and removed from the instrument without use of special tools.

Further objects and advantages are within the scope of this invention such as relate to the arrangement, operation and function of the related elements of the structure, to various details of construction and to combinations of parts, elements per se, and to economies of manufacture and numerous other features as will be apparent from a consideration of the specification and drawing of a form of the invention which may be preferred, in which:

Figure 1 is a side view of a preferred form of holder having a hinged loop or bail adapted to slip over a finger of the user's hand;

Figure 2 is a rear elevational view of the holder as shown in Figure 1;

Figure 3 is a side elevational view showing another form of holder;

Figure 4 is a rear elevational view of the holder shown in Figure 3;

Figure 5 is a side elevational view illustrating a modified form of holder;

Figure 6 is a rear view of the holder shown in Figure 5;

Figure 7 is a side elevational view of another form of holder.

Figure 8 is a rear elevational view of the structure shown in Figure 7;

Figure 9 is a side elevational view showing a further form of the invention;

Figure 10 is a rear view of the device shown in Figure 9;

Figure 11 is a side elevational view of a further modified form, and

Figure 12 is a rear elevational view of the structure shown in Figure 11.

While I have illustrated the forms of my invention as utilized as holders for a chronometer

2

of the pocket-watch type, it is to be understood that I contemplate use of my invention wherever the same may be found to have utility.

Referring to the drawings in detail, with particular reference to Figures 1 and 2, there is illustrated a watch or instrument case W provided with stem S and bail B having a holder 15 attached thereto.

The holder 15 is preferably made of metallic tempered wire frame 14 and is inclusive of leg portions 16 having projecting end portions 17 of somewhat arcuate form to engage or embrace the lower side wall region of the watch or instrument case with resilient force. At the upper end of the frame 14 is a loop or hook 18 by means of which the holder 15 is initially hooked to the bail B of the watch case. Connecting legs 19 and 20 forming the body of the frame are contiguous arranged adjacent the flat rear face 20 of the watch case. The leg 20 is formed with eyes 21 formed by configuring the wire for the purpose of receiving a finger loop or U-shaped member 22. The finger grip 22 as shown is provided with projecting ends 23 for pivotal engagement with the eyes 21 to permit hinging or folding back of the finger grip 22 against the case in a position out-of-use.

In Figures 3 and 4, I have shown an instrument holder 25 formed of metallic wire but of one piece construction. In this form, the lower leg portions 26 having arcuate end portions 27, hook 28, and a pair of finger loops 29 are formed from a single continuous wire. In this form of the invention the finger grips or loops 29 provide a degree of resilience to maintain the holder in engagement with the instrument case. A further advantage with this construction lies in the fact that this holder may be used as a pedestal for mounting the watch upon a horizontal support or table with the finger-grip loops 29 in contact with the table.

In Figures 5 and 6, there is illustrated a form of the invention in which a body portion or frame 32 is formed of sheet metal and is configurated with outwardly-extending arcuately shaped tabs or projections 33 for engagement with the peripheral contour of the watch or instrument case. The upper portion of the sheet metal frame is formed with a reversely bent tab 34 having a hook or hook-like extremity 35 for engagement with the bail B of the watch case. The reverse bend portion 34 provides the resilience for initial attachment of the holder to the watch as well as to retain the holder on the watch. The frame 32 is formed with spaced, struckup lateral projections or ears 36 to receive the projecting ends of loop 22 for attachment to a finger of the user's hand.

The above described holders may be quickly and easily attached to the watch or instrument

case by first engaging the hook 18, 28 or hook 35 with the bail B, then flexing the lower members 17, 27 or 33 downwardly and outwardly around the peripheral edges of the instrument case W.

Some types of stop watches are fitted with a side mounted brake or "stop" means M as shown in Figures 7 and 8. Furthermore a suspension means, strap or other device L may be attached to the bail of the watch and so make it inconvenient to attach the above described holders thereto. Figures 7 and 8 illustrate a form of the invention to overcome these difficulties in which a stamping or frame 40 of light gage metal is provided with lower leg portions 41 having arcuately formed ends 42 adapted to fit over the periphery of the watch case W. The upper portion is formed with a bifurcated hook portion 43 adapted to straddle the stem S of the watch case and snap over the upper edge of the case so as not to interfere with the operation of the brake button M at the side of the case. Spaced ears 45 having openings 46 are struck up from the frame 40 to pivotally receive the finger loop 22 and to permit its folding back against the case to a position out-of-use.

Figures 9 and 10 illustrate a form of the invention in which the method or means of securing the holder to the instrument is not entirely dependent upon the inherent flexural strength of the parts. As shown in Figures 9 and 10, the upper end of the frame plate 40 is formed with outwardly-extending ears 50 having threaded openings 51 for the reception of screws 52. A plate 53 having a hook-like portion is adapted for engagement with the bail B of the watch. The plate is formed with an outwardly extending ledge 54 having openings 55 to accommodate the screws 52 for fastening the frame 40 and hook member 53 to the watch. In this form I have shown portions struck up from the body 40 to form sockets 56 for the reception of the projections of the finger loop 22a.

Figures 11 and 12 illustrate a construction similar to the construction shown in Figures 9 and 10 formed to accommodate instrument cases of the character shown in Figures 7 and 8. In this form, the frame consists of a sheet metal stamping 60 in combination with a member 61 having a bifurcated portion adapted to straddle the stem S and having an outwardly formed ledge 63 provided with openings to accommodate screws 64 whereby the holder may be attached to the watch case W, the screws extending into threaded openings formed in ears 65 extending from the frame 60. The frame is formed with struck-up mid portions 64' to provide a pivotal connection with the ends of the finger loop 22b so as to permit folding the loop flatwise against the watch case when not in use. In order to resiliently maintain the loop 22 in a finger-receiving position or in a folded position out-of-use, I have provided notches or recesses 66 in the outer edges of the pockets 64' whereby the loop 22 may be resiliently snapped into or out of engagement with the notches to retain the loop in desired position.

While I have described my invention as being formed of metal, the same may also be made of other materials as for example plastics or the like without departing from the spirit of the invention.

It is apparent that, within the scope of the invention, modifications and different arrangements may be made other than is herein disclosed, and the present disclosure is illustrative merely, the invention comprehending all variations thereof.

What I claim is:

1. A holding means for an instrument case, including a frame formed of wire; said frame including angularly divergent spaced resilient portions arranged to take over the periphery of the case; and a finger encircling member integrally connected to said frame.

2. In a timepiece holder having a frame, the combination of at least three laterally divergent arms having generally arcuately shaped resilient terminal portions adapted to embrace the periphery of the timepiece, and a rearwardly extending finger loop associated with the frame for reception of a finger of the user, said loop being secured intermediate said terminal portions whereby the time piece is disposed in the palm of the user's hand.

3. A holder according to claim 2 wherein said finger loop is hingedly connected to said frame.

4. A holder according to claim 2 wherein said frame is formed of sheet metal and said arms are formed by projections thereof.

5. A holder according to claim 2 wherein said arms are formed of sheet metal and are adapted to frictionally engage said timepiece.

6. A holder according to claim 2 wherein said frame comprises spaced projections extending therefrom, said projections having openings therein, and said loop being of U-shaped configuration and having portions extending into said openings for pivotally connecting said loop to said frame.

7. A holder according to claim 2 for a timepiece having a bail adjacent its periphery, one of said arms being engageable with said bail.

8. In a timepiece holder having a frame, the combination of laterally divergent arms having generally arcuately shaped terminal portions adapted to embrace the timepiece at at least three spaced points next adjacent the periphery of said timepiece, and a rearwardly extending finger loop associated with the frame for reception of a finger of the user, said loop being secured intermediate said terminal portions whereby the timepiece is disposed in the palm of the user's hand.

VICTOR E. HOFMANN.
